Des. 206,153
Patented Nov. 8, 1966

206,153

PICK-UP CAMPER

Roberta L. Dexter, R.R. 2, Bristol, Ind.

Filed Nov. 12, 1965, Ser. No. 88,076

Term of patent 14 years

(Cl. D14—3)

FIG. 1

FIG. 2

FIG. 3

FIG. 4

I claim:

The ornamental design for a pick-up camper, substantially as shown.
